UNITED STATES PATENT OFFICE.

MICHAEL L. FARRY, OF BOSTON, MASSACHUSETTS.

HORSESHOE.

1,378,942.

Specification of Letters Patent.

Patented May 24, 1921.

Application filed May 22, 1920. Serial No. 383,347.

To all whom it may concern:

Be it known that I, MICHAEL L. FARRY, a citizen of the Republic of Czechoslovakia, and resident of Hyde Park, city of Boston, 5 county of Suffolk, and Commonwealth of Massachusetts, have invented an Improvement in Horseshoes, of which the following description, in connection with the accompanying drawings, is a specification, like 10 characters on the drawings representing like parts.

This invention relates to horseshoes and aims to provide a novel detachable calk therefor which may readily be applied and 15 removed with an ordinary wrench or like tool.

In the drawings of one embodiment of my invention selected for description and illustration herein:

20 Figure 1 is a plan of the lower face of a substantially conventional horseshoe with my novel calks secured thereto;

Fig. 2, a cross-section on the line 2—2 of Fig. 1, looking in the direction of the arrow; 25

Fig. 3, a perspective of the toe calk detached;

Fig. 4, a similar view of the heel calk;

30 Fig. 5, a similar view of one of the wedge locking members;

Fig. 6, a plan of a shoe showing a modified form of securing the calks thereto;

Fig. 7, a plan of the lower face of the shoe with the calks and strut member re- 35 moved;

Fig. 8, a similar view showing rubber or other resilient calks secured to the shoe;

Fig. 9, a longitudinal section on the line 9—9, Fig. 8, from the left;

40 Fig. 10, a cross-section on the line 10—10, Fig. 8, looking down; and

Fig. 11, a side or edge view of the strut.

Referring first to Figs. 1 to 5 my invention comprises a pair of slightly crescent- 45 shaped wedge locking members *f*, each having on one edge a beveled or wedge-shaped flange *g* adapted to be inserted between the hoof and the upper face of the side members *a* of the shoe.

50 While it is usually possible to insert this flange between the shoe and hoof without special difficulty I prefer, when possible, to have the upper face of the shoe adjacent its inner edge beveled slightly as shown at

55 *g*², Fig. 2, when the shoes are put on to facilitate the use of the calks.

Each locking member *f* is tapped and threaded as at *h* and *h*¹ at or near its ends (Figs. 5 and 7) to receive a bolt and nut *i* by means of which a toe-calk plate *b*' and heel-calk plate *e* may be secured thereto, they being tapped at *b*², *b*³, and *c*', *d*', respectively, for the purpose.

While the locking members will usually stay in position without assistance, nevertheless to avoid the danger of slipping, I may use a strut member *o* (Figs. 1, 2, 10 and 11), the ends of which (Figs. 2, 7) are reduced in thickness at *o*' sufficiently to overlie and fit snugly the central depressed sections *f*² of the members *f*, the top of the strut being substantially flush with the lower face of the shoe.

The front and rear edges of the strut are preferably beveled at *o*² (Fig. 11) to permit them to slide under similarly beveled edges *b*⁴ of the calk plates *b*', *e*, and thus aid in retaining the strut in position. Or (Figs. 8, 9, 10) if a pad *p* of rubber or canvas with rubber calks is used, as is frequently done, 80 this pad will securely hold the strut in place.

The plates *b*' and *e* may have the calks *b*, *d* and *c* or any desired type of calks.

The method of applying my novel locking 85 members and calks is as follows: The locking members with bolts having their heads upon the inner or upper face thereof are placed within the sides of the shoe and the beveled flanges *g* slipped beneath the bevelled edges *g*² of the shoe.

Next the strut *o* is positioned between the members *f* with the thin ends *o*' overlying the thin central portions *f*² of the member *f*. Thereafter the toe and heel plates *b*, *e*, are 90 positioned, the nuts are set up on the bolts *i* and the shoe is ready for use.

The calks may be applied or removed in a few minutes with the aid of a wrench or pair of pliers.

In Fig. 6, I show a modified form of construction wherein the shoe is tapped to receive the bolts and nuts and the calk plates are fastened directly to the shoe without the use of locking members.

While I have shown herein one embodiment of my invention, it is to be understood that my invention is not to be limited in all details to the construction shown and described.

Claims.

1. A horseshoe having removable calks,

100

105

110

locking members adapted to fit the side of the shoe, and means for locking the calks to the locking members.

2. A horseshoe having removable calks, 5 locking members fashioned to fit and overlie the shoe, and means for locking the calks to the locking members.

3. A horseshoe having removable calks, 10 locking members having flanges fashioned to fit and overlie the inner side edges of the shoe, and means for locking the calks to the locking members.

4. A horseshoe having removable calks, locking members adapted to fit the shoe, a

strut to wedge the locking members apart 15 and in locking engagement with the shoe, and means for locking the calks to the locking members.

5. A horseshoe having removable calks, locking members adapted to fit the shoe, a 20 strut to overlie the locking members and also to wedge them apart into locking engagement with the shoe, and means for locking the calks to the locking members.

In testimony whereof, I have signed my 25 name to this specification.

MICHAEL L. FARRY.
